UNITED STATES PATENT OFFICE.

FRODE H. PIERSON, OF NEW HAVEN, CONNECTICUT.

RATCHET-DRILL.

1,315,638.

Specification of Letters Patent.

Patented Sept. 9, 1919.

Application filed March 3, 1919. Serial No. 280,444.

To all whom it may concern:

Be it known that I, FRODE H. PIERSON, a citizen of the United States, residing at New Haven, in the county of New Haven and 5 State of Connecticut, have invented a new and useful Improvement in Ratchet-Drills; and I do hereby declare the following, when taken in connection with the accompanying drawings and the characters of reference 10 marked thereon, to be a full, clear, and exact description of the same, and which said drawings constitute part of this application, and represent, in—

Figure 1 a side view of a ratchet drill 15 constructed in accordance with my invention, the end of the handle being broken away.

Fig. 2 an underside view of the same.

Fig. 3 a top or plan view thereof.

20 Fig. 4 a sectional view on the line 4—4 of Fig. 3.

Fig. 5 a broken view illustrating the operation of the feeding pawl.

Fig. 6 a side view of a modified form of 25 operating nut.

This invention relates to an improvement in ratchet drills and particularly to ratchet drills adapted to be operated by hand and where considerable power is necessary, the 30 object of the invention being to provide means whereby the drill is not only turned to cut, but the drill is fed longitudinally so as to continue the cutting without other means for feeding; and the invention consists in the construction hereinafter 35 described and particularly recited in the claims.

In carrying out my invention, I employ a head 10 recessed to form a chamber 11 and 40 provided at its upper edge with an outwardly projecting flange 12. Extending through the lower end 13 of the chamber is a threaded post 14 of a chuck 15 adapted to receive and contain a drill 16. On this 45 threaded post is a long nut 17 which projects upward above the upper end of the head and on this nut, which is angular, is a ratchet washer 18 by which the nut may be turned and through which the nut may have 50 longitudinal movement. This ratchet rests upon the upper edge of the head and may be held securely in connection therewith by means of a dog 19. Mounted around the 55 head is a collar 20 which bears against the underside of the flange 18 and is held in place by a lock-nut 21 so that the collar is

free to rotate. This collar is formed on one side with an outwardly projecting lug 22 in which is mounted an upwardly projecting pin 23 and the collar is also formed with an outwardly projecting boss 24 formed with a chamber 25 and with an opening 26 from the chamber through the outer end of the boss. In this chamber is a radially movable pawl 27 adapted to engage with ratchet 60 teeth 28 on the outer surface of the upper part of the head. This ratchet is formed with a stem 29 projecting outward through the opening 26, and in the projecting end of the stem is a handle pin 30 adapted to ride 70 upon the end of the boss or enter the notch 31 therein so as to permit the pawl to engage with the teeth on the head or be withdrawn for engagement therewith, the pawl being normally forced into engagement with 75 the ratchet by means of a spring 32. Mounted upon the pin 23 is a handle 33, this handle being formed with a segmental arm 34 in which is mounted an adjusting screw 35 for the purpose as will hereinafter appear, and 80 also connected with the handle is a pawl 36 adapted to engage with the teeth of the ratchet washer 18. This pawl is normally held in engagement with its ratchet by means of a spring actuated plunger 37 85 mounted in the end of the handle in line with the hub 38 of the pawl which is formed with a notch 39 into which the end of the plunger 37 may enter so as to lock the pawl out of engagement with the ratchet washer 90 18. Mounted in the upper end of the nut 17 is a centering point 40, and it may here be mentioned that the terms "upper" and "lower" are relative terms as the device may be operated in any position. The ratchet 95 drill is used in connection with a frame or holder of some kind consisting of a bearing 41 for the point 40 and an anvil 42 upon which the work may rest.

In operation the handle is first turned 100 until the end of the screw 35 comes in contact with the side of the collar or with the side of the lug thereon, and the time of contact will be determined by adjusting the screw 35. This movement determines the 105 extent of backward movement of the pawl 36. On the first forward movement of the handle, the pawl 36 engaging with the ratchet washer 18, turns the nut 17 on the stem 14 of the chuck 15 so as to turn the nut 110 off from the stem so as to extend the point 40 and force it against its bearing 41, or in

other words, to force the drill downward without turning it. The handle then comes into contact with the collar 20, and as the pawl 24 is in engagement with the teeth 28 5 that collar will be turned so as to turn the head and with it the chuck and the drill.

For the purpose of adjustment the pawl 24 may be withdrawn so that the collar is free to be turned on the head without moving the drill. It will thus be seen that in 10 the first movement of the handle the drill is first advanced and then the power applied for cutting. While I prefer to form the ratchet washer separate from the nut, the 15 nut itself may be circular in cross-section and formed with ratchet teeth 43 as shown in Fig. 6 of the drawings, the pawl co-acting with these teeth in the same way as with the teeth on the ratchet washer, the 20 operation of the device being exactly the same in both cases.

I claim:—

1. A ratchet drill comprising a head provided with external ratchet teeth and formed 25 with a chamber, a chuck connected with said head and formed with a threaded post extending upward through said chamber, a nut on said post, a collar mounted on said head, a pawl carried by said collar and engaging with the teeth on the head, a handle pivotally connected with said collar and adapted to turn the same, a pawl mounted on said handle and adapted to turn said nut.

35 2. A ratchet drill comprising a head formed with a chamber and with external ratchet teeth, a chuck connected with said head and formed with a threaded post ex-

tending upward through said chamber, a nut on said post, a collar surrounding said head, 40 a spring-actuated pawl mounted in said collar and adapted to engage with the ratchet teeth on the head, said collar formed with an outwardly projecting arm, a pin carried by said arm, a handle mounted on 45 said pin, an adjusting screw mounted in said handle and adapted to engage with said collar, a pawl also mounted on said handle and adapted to turn said nut.

3. A ratchet drill comprising a head 50 formed with a chamber with an outwardly extending flange at its upper end and with external ratchet teeth, a chuck connected with said head and formed with a threaded post extending upward through said chamber, 55 a nut on said post, a ratchet washer on said nut, a collar surrounding said head and held in engagement therewith, a spring pawl mounted on said collar and adapted to engage with the ratchet teeth on the head, a handle pivotally connected with said collar, 60 said handle provided with a stop adapted to limit the movement of the handle with relation to the collar, a pawl connected with said handle and extending into engagement 65 with said ratchet washers, and a spring plunger adapted to hold said pawl in engagement with the ratchet washer.

In testimony whereof, I have signed this specification in the presence of two subscribing 70 witnesses.

FRODE H. PIERSON.
